UNITED STATES PATENT OFFICE.

SUSAN G. COBURN, OF BUFFALO, NEW YORK.

LAUNDRY-BAG.

No. 821,986.

Specification of Letters Patent.

Patented May 29, 1906.

Application filed October 6, 1905. Serial No. 281,586.

To all whom it may concern:

Be it known that I, SUSAN G. COBURN, a citizen of the United States, residing at Buffalo, in the county of Erie and State of New York, have invented certain new and useful Improvements in Laundry-Bags; and I do hereby declare the following to be a full, clear, and exact description of the invention, such as will enable others skilled in the art to which it appertains to make and use the same, reference being had to the accompanying drawings, and to figures of reference marked thereon, which form a part of this specification.

My invention relates to improvements in laundry-bags, its object being to provide a construction whereby the bag can be instantly emptied of its contents.

To that end my invention consists of certain details of construction, all of which will be fully hereinafter described and claimed.

In the drawings, Figure 1 is a front elevation of my improved bag. Fig. 2 is a central vertical section taken in the line xx of Fig. 1. Fig. 3 is a side elevation of Fig. 1.

Referring to the drawings, 1 is the bag, of any suitable fabric, and preferably of rectangular configuration, provided along its upper edge with the stiffening-rod 2, of wood or metal, and embedded within the material of the bag.

3 is a loop, centrally secured to the upper edge of the bag for suspending the same from a hook.

4 is a centrally-arranged vertical slit in one of the faces of the bag, through which the soiled clothes are inserted.

The lower edges of the opposite faces of the bag are unattached, thus forming an open bottom, through which to remove the contents of the bag. One of the lower edges of the bag extends beyond the other edge, forming a flap 5, adapted to be removably secured by any suitable fastening devices 6 to the bag to close the same.

In operation when it is desired to empty the bag it is only necessary to loosen the flap 5, when the contents will drop or can be quickly shaken from the bag. The flap 5 is then refastened and the bag suspended from its hook ready for refilling.

My improved bag is equally well adapted for the reception of waste-paper, scraps, &c.

I claim—

A laundry-bag provided with an open bottom, a stiffening-rod across its upper edge, a central vertical slit in one of its faces and a flap along one of its lower edges, adapted to be removably secured to the other lower edge of the open bottom, to close the same, as and for the purpose stated.

In testimony whereof I have signed my name to this specification in the presence of two subscribing witnesses.

SUSAN G. COBURN.
